BOBBIN

Rexford P. Bennett, Honesdale, Pa., assignor to
The Formica Company, a corporation of Ohio

Application August 31, 1949, Serial No. 113,270

5 Claims. (Cl. 242—124)

1

This invention relates to bobbins for use on textile winding and twisting machines, and in particular it relates to bobbins having characteristics which make them especially suitable for use in high speed machinery and with modern synthetic yarns such as nylon which have a very high contractive force.

The principal object of the invention is to provide a bobbin in which a core of light metal such as aluminum forms a central assembly member to which are affixed a relatively thin non-metallic bobbin barrel and bobbin heads, in order that the assembled bobbin may be light, yet strong, rigid, and well balanced.

Another object is to provide a bobbin which is substantially free of any tendency to distort under the contracting force of nylon or other synthetic yarn, and which will not damage the yarn by snagging or catching it.

Another object is to provide a bobbin which may be readily disassembled into its component parts so as to facilitate repair of the bobbin in case of wear or damage.

Because of the light weight and excellent balance which are made possible by the use of a lightweight metal core, the improved bobbin may be satisfactorily employed on spinning machines which operate at speeds of 10,000 to 16,000 R. P. M. or higher, and even at such speeds has almost no tendency to wobble, vibrate, or climb the spindle blade.

The invention is illustrated in a preferred embodiment in the accompanying drawing, in which: Fig. 1 is a longitudinal sectional view of the bobbin mounted on a tapered spindle; Fig. 2 is an enlarged fragmentary sectional view of one end of the bobbin, showing the details of assembly; and Figs. 3 and 4 are fragmentary sectional views similar to Fig. 2 showing alternative arrangements for securing the core header to the bobbin core.

The central element of the bobbin is a lightweight metal core, preferably formed of aluminum, having permanently secured within it a continuous sleeve of laminated plastic material which receives the spindle blade of a textile machine. The use of a laminated plastic, or other non-metallic sleeve avoids the smudging of the spindle blade which is inevitable if a metal bearing is used. Likewise, the plastic sleeve has no tendency to cling or seize when the bobbin is being removed from a tapered spindle blade, and is extremely stable and free of interval distortion under extremes of heat and humidity. The sleeve may be either straight or tapered, depend-

2

ing upon the type of spindle on which the bobbin is to be used.

A light metal core header is secured to each end of the core, and the headers receive the barrel and bobbin head assembly as will be described in detail.

Referring to the drawings, an aluminum or other lightweight metal core 5 is provided with a fixed non-metallic sleeve 6, said sleeve preferably being composed of laminated plastic impregnated with a binder and being secured within the metal core 5 by spinning over the ends of the core as at 7, and being of suitable shape and dimensions to fit snugly on the spindle blade 8 of a textile machine. In the preferred form shown in Figs. 1 and 2, the metal core 5 has threads 80 at its end portions to receive lightweight annular metal core headers 9 which have their outer faces annularly shouldered at 10.

In order to assure alignment, concentricity and balancing of the core and core headers, they are preferably assembled rough, and machined from a single center after assembly.

A bobbin barrel 11 is so proportioned that it fits snugly on the core headers 9 and has its ends flush with the outer faces of said headers. The barrel likewise is composed of a non-metallic material, preferably a laminated plastic impregnated with a binder. The barrel should be of a material which will remain undistorted at temperatures of 225° F. and moisture conditions of 100% relative humidity.

A pair of annular compressible washers 12 and 13 surround the annular shoulders 10 of the core headers 9 and overlie the ends of the bobbin barrel 11.

Laminated plastic bobbin heads 14 and 15 overlie the washers 12 and 13, respectively, and are screwed to the core headers 9 by means of a plurality of screws 16. The inner face of each bobbin head is provided with an annular shoulder 17 to engage the shoulder 10 of the core header 9 so as to assure concentricity of the bobbin head. The screws 16 are drawn up very tightly in order to grip the barrel 11 firmly and lock it against longitudinal movement. Likewise, the firm grip compresses the washers 12 and 13 so that they fill any irregularities in the abutting surfaces of the barrel 11 and bobbin heads 14 and 15, thus avoiding any possibility of yarn being caught or snagged in a crack between the barrel and the bobbin heads.

A small cup-shaped metal ring traveler guide 18 is pressed into the end of the bobbin, as seen

in Fig. 1, to control yarn tension in the usual way.

Figs. 3 and 4 illustrate modified arrangements for securing the core headers to the metal core. In the form shown in Fig. 3, the metal core 25 is tapered at 26 to retain the sleeve 6 in place, and has flared ends 27 to engage a wedging face 28 of a core header 29, thus securing the header firmly between the taper 26 and the flared ends 27. The remainder of the assembly is identical with that shown in Figs. 1 and 2.

In the form shown in Fig. 4, a metal core 35 is flared outwardly at 36 to engage a complementary arcuate face 37 on the inner periphery of a core header 38, and is spun inwardly at its outer extremity 39 to engage the non-metallic sleeve 6. In all other respects, the modification of Fig. 4 is similar to the bobbin illustrated in Figs. 1 and 2.

The foregoing detailed description is given for clearness of understanding only and no unnecessary limitations should be understood therefrom as modifications will be obvious to those skilled in the art.

I claim:

1. A bobbin, comprising: a cylindrical metal core provided with a fixed, continuous non-metallic internal sleeve which is adapted to fit snugly on the spindle blade of a textile machine; a pair of annular metal core headers of substantially larger diameter than said metal core concentrically secured to the ends of the core, said core headers having continuous outer surfaces of substantial area; a non-metallic bobbin barrel secured snugly on the core headers so as to be positioned thereby in concentric spaced relation to said metal core, said barrel having ends affording surfaces which are continuous with those on said headers; a pair of compressible annular washers overlying the ends of the barrel; a pair of non-metallic bobbin heads having continuous inner surfaces which abut against said washers and the outer surfaces of the core headers; and a plurality of removable fastening members spaced outwardly from the core to detachably secure said bobbin heads firmly against said core headers and compressible washers to exert a compressive force on the washers and on the ends of the said barrel.

2. A bobbin according to claim 1 wherein the core headers make threaded engagement with the core and the bobbin heads are bolted to the core headers.

3. A bobbin according to claim 1 wherein the core is tapered adjacent its ends to grip the sleeve and has flared ends, and the headers are firmly gripped between said tapers and said flared ends.

4. A bobbin according to claim 1 wherein the core is flared adjacent its ends to engage complementary arcuate faces on the inner periphery of the core headers, and is tapered at its ends to grip the sleeve.

5. A bobbin comprising: a cylindrical metal core provided with a close fitting internal lining comprising a fixed, continuous sleeve of laminated plastic which is adapted to fit snugly on the spindle blade of a textile machine; a pair of annular metal core headers of substantially larger diameter than said metal core concentrically secured to the ends of the core, said headers having outer surfaces of substantial area provided with concentric shoulders, and said core and headers forming a central frame for the bobbin; a bobbin barrel of laminated plastic secured snugly on said core headers so as to be positioned thereby in concentric spaced relation to said metal core, said barrel having ends affording annular surfaces which are continuous with those on said headers; a pair of compressible washers surrounding the shoulders on the core headers and overlying the ends of the bobbin barrel; a pair of laminated plastic bobbin heads having concentric shoulders complementary to the shoulders on said core headers and inner surfaces which abut against the headers and the washers; and a plurality of screws extending through said bobbin heads and washers to detachably secure the heads firmly to said headers to exert a compressive force on the washers and bobbin barrel.

REXFORD P. BENNETT.
